Patented July 7, 1914.

UNITED STATES PATENT OFFICE.

JOSEPH J. HEIM AND WILLIAM NOTTBURG, OF KANSAS CITY, MISSOURI.

FROST-REMOVER.

1,102,336.

Specification of Letters Patent.

Patented July 7, 1914.

Application filed December 12, 1912. Serial No. 736,326.

To all whom it may concern:

Be it known that we, JOSEPH J. HEIM and WILLIAM NOTTBURG, citizens of the United States, residing at Kansas City, in the county of Jackson and State of Missouri, have invented certain new and useful Improvements in Frost-Removers, of which the following is a specification.

Our invention relates to improvements in frost removers.

The object of our invention is to provide a simple and efficient mechanism for removing frost, snow or ice from window panes, transparent automobile wind shields and the like.

Our invention is particularly adapted for use on street or railway cars which are equipped with electrical power and air brake mechanism.

20 In the accompanying drawings which illustrate the preferred form of our invention, Figure 1 is a view partly in vertical section and partly in side elevation of the apparatus. Fig. 2 is a front view of the nozzle.

Similar characters of reference designate similar parts in the different views.

In the drawings we have shown our invention applied to a car, 1 designating the car body and 2 the vestibule. Supported by the body is an ordinary air pump such as is commonly employed in air brake mechanisms. The pump, which is designated by 3 is connected by a conductor 4, having a 25 check valve 5, with a receiver 6 which is connected with a conductor 7 which includes a chamber 8 and a flexible discharge portion 9 having a nozzle 10. In the chamber 8 may be located electrical heating means 40 comprising a suitable resistance device 11 which may be connected to the circuit from which the motor of the car, not shown, derives its current. Intermediate of the receiver 6 and chamber 8 is a regulating valve 12 forming a part of the conductor 7 and serving to limit the pressure of the air passing through the nozzle 10 to that desired. Intermediate of the valve 12 and chamber 8 is a branch pipe 13 to which is connected 45 any suitable pressure indicating gage 14, the pipe 13 being connected to the conductor 7. For movably supporting the flexible portion 9 is a cord 15 one end of which is secured to the portion 9 by a suitable clip or 50 fastening device 16, and the other end of

which supports a weight 17, pulleys 18 and 19 fastened to the under side of the roof 20 of the vestibule being provided for supporting the cord 15. Preferably the weight 17 is sufficiently heavy to lift the flexible portion 9. The flexible portion 9 is adapted to be drawn downward to a position in which the nozzle 10 will discharge heated air upon the inner side of a window pane 21 with which the front wall of the vestibule 2 is 60 provided.

In the operation of our invention the air passing from the pump 3 to the receiver 6 by way of the conductor 4 and past the check valve 5, and from the receiver to the 70 chamber 8 is heated in the chamber 8 and escapes from the discharge portion 9 by way of the nozzle 10. If the nozzle is drawn downwardly to a position in which the heated air can impinge against the pane 21, any 75 frost, snow or ice thereupon will be melted, so as to permit the motorman to look through the window. After the snow, ice or frost has been cleared from the window pane, the nozzle 10 is released, upon which 80 the counter-balance weight 17 will draw upwardly the flexible portion 9, so that it and the nozzle 10 will not be in the way of the motorman.

We do not limit our invention to the structure shown and described, as modifications, within the scope of the appended claims, may be made without departing from the spirit of our invention.

Having thus described our invention, what 90 we claim and desire to secure by Letters Patent, is:—

1. In a frost remover, the combination with a car vestibule having a window pane, of a conductor having a flexible discharge portion movable toward and from a position in which it will discharge air against said pane, means for normally moving said flexible portion from said position, means for heating the air in said conductor, a receiver 95 connected with said conductor, a regulating valve intermediate of the receiver and the heating means, an air pump, a conductor connecting the receiver and air pump, and a check valve in the last named conductor. 100

2. In a frost remover, a car, a tank carried by the car and adapted to contain air under pressure, a conductor connected with said tank and having a nozzle arranged to discharge air against a window pane, means 110

for controlling the flow of air through said conductor, and means for heating the air which passes through said conductor.

3. In a frost remover, a car, a tank carried thereby and adapted to contain air under pressure, a conductor connected with said tank and having a nozzle arranged to discharge air against a window pane, means for controlling the flow of air through said conductor, and electrical means for heating said air.

4. In a frost remover, a car, a tank carried thereby and adapted to contain air under pressure, a conductor connected with said tank and having a nozzle arranged to discharge air against a window pane, the conductor having a heating chamber, electrical means in said chamber for heating the same, and means for controlling the flow of air through said conductor.

5. In a frost remover, a car, a conductor provided with a flexible portion having a nozzle, means carried by said car for supplying said conductor with air under pressure, means for heating said air, and yielding means for normally holding the nozzle in a raised position.

6. In a frost remover, a car, a conductor having a nozzle, means carried by the car for supplying heated air under pressure to said nozzle through said conductor, and means for controlling the flow of air through said conductor.

7. In a frost remover, a car, a conductor provided with a flexible portion provided with a nozzle arranged to discharge air against a window pane, and means for sup-

plying heated air under pressure to said nozzle through said conductor, said means being carried by said car.

8. In a frost remover, a car, a conductor carried thereby and provided with a flexible portion provided with a nozzle, a weight, means by which said weight normally lifts the nozzle to a raised position, and means for supplying heated air under pressure to said nozzle through said conductor.

9. In a frost remover, a car, a tank carried thereby and adapted to contain air under pressure, a conductor connected with said tank and having a flexible portion provided with a nozzle, a valve for controlling the flow of air through said conductor, means for heating the air passing through the conductor, and means carried by the car for supplying the tank with air under pressure.

10. In a frost remover, a car, a tank carried thereby and adapted to contain air under pressure, a conductor connected with said tank and having a flexible portion provided with a nozzle, a valve in said conductor controlling the flow of air therethrough, means for heating the air passing through the conductor, and yielding means for normally raising the nozzle to a raised position.

In testimony whereof we have signed our names to this specification in presence of two subscribing witnesses.

JOSEPH J. HEIM.
WILLIAM NOTTBERG.
